FUNNEL GUIDE ALIGNMENT INDICATOR

Charles W. Derk, Lewistown, Pa., assignor to
American Viscose Corporation, Wilmington,
Del., a corporation of Delaware

Application March 13, 1951, Serial No. 215,296

7 Claims. (Cl. 57—76)

1

The present invention relates to centrifugal spinning equipment and particularly to the centering of a strand delivery device with respect to the axis of rotation of a centrifugal strand collector. The invention is applicable to any equipment wherein the strand is delivered to the collector through a straight passageway of a guide device and is hereinafter described with particular reference to a funnel guide and a spinning bucket of the type used generally for the collection of yarn packages or "cakes" of regenerated cellulose rayon.

It is an object of the invention to provide apparatus for accurately centering the yarn-discharging end of a funnel guide stem along the axis of rotation of a spinning bucket over which the guide is supported, or for positioning a holder for the guide to obtain accurate centering of said yarn-discharging end. It is another object to provide a simple and inexpensive device which facilitates the adjustment of a funnel guide holder whereby the guide may be supported with a desired axial alignment and the traverse range of the guide may be spaced a desired distance from the bottom of a spinning bucket. Other objects, features and advantages will become apparent from the following description of the invention and the drawing relating thereto in which

Fig. 1 is in section view of a funnel guide, a holder therefor, and a spinning bucket, and a device (not sectioned) for aligning the guide in accordance with the invention;

Fig. 2 is a fragmentary view in section of a funnel guide holder of Fig. 1 and a jig for positioning the holder; and

Fig. 3 is a top view of the jig shown in Fig. 2.

The present invention is concerned with an implement or device that may be supported in a funnel guide or a holder therefor for the purpose of obtaining accurate alignment and centering of the strand-discharging end of a guide supported by the holder with respect to the axis of rotation of a spinning bucket. In accordance with one form of the invention, an indicator spindle extends through a strand guide having a straight elongate passageway for the passage of strand, and into engagement with the interior bottom surface of the spinning bucket. The spindle is rotated by the bucket surface, when being rotated, to indicate by the rapidity of rotation the accuracy with which the end of the guide is centered within the bucket. In accordance with another form of the invention, a jig comprising an elongate shank portion, and an indicator spindle extending axially there-

2

through is temporarily supported by the holder in lieu of the guide for the purpose of indicating the desired position and alignment of the holder whereby the guide will be accurately aligned and centered on said axis when supported by the holder. A level indicator is optionally included in the structure of the jig.

In the drawing, a funnel guide 1 comprising a funnel 8 and a ferrule 5 is supported over the center of the interior bottom surface of the bucket 2 by a holder comprising a bracket 3, and a sleeve 4 in threaded relationship with an exteriorly threaded bushing 5. A ferrule 6 is secured along the stem of the funnel 8 at a predetermined position. The ferrule has an outer surface which is complementary to the inner surface of the bushing and permits the funnel guide 1 to be easily inserted and withdrawn from the bushing. As shown, the complementary surfaces of the ferrule and the bushing are smooth and cylindrical. As a result of the threaded relationship of the sleeve 4 with the bushing 5, the bushing may be turned to obtain any desired vertical adjustment of the guide 1 with respect to the bottom of the bucket. The sleeve 4 has a flange 7 which seats on the upper flat surface of the bracket. The exteriorly and interiorly threaded body portion of the sleeve 4 extends through an aperture 11 of the bracket having a much larger diameter so that the bushing, and the guide supported therein may be adjusted relative to the bracket in a direction laterally with respect to the axis of the bucket. The stem 8 of the funnel is hollow to provide a passageway 9 which is constricted at several points therealong by inner annular ridges 10 which limit the contact of yarn passing through the guide to several points so as to minimize frictional drag imposed on the yarn.

In accordance with the invention, an indicator spindle 12 is provided having a straight shank portion 13 adapted to be inserted through the passageway 9 of the guide and having a portion 14 extending at an angle with the shank portion. The spindle 12 terminates in a substantially flat surface at 15 which engages the generally flat bottom surface of the bucket. The shank portion has a diameter such that it may be easily inserted into, or withdrawn from, the guide. The spindle 12 rotates easily within the guide upon application of a rotative force to the surface 15. The shank portion of the spindle is constructed, preferably with as large a diameter as the passageway of the funnel guide stem will permit without binding or frictionally restricting the rotation of the spindle and so that the spindle

will rotate on a definite axis without wobble. The axis of rotation of the bucket may be thus ascertained with greater precision while adjusting the spindle in a lateral direction.

When the guide is aligned in an off-center position with respect to the axis of the bucket 2, the spindle 12 engages a circular path on the bottom of the bucket. In such a position, very little or no rotative force is applied to the spindle. However, as the position of the funnel is shifted in a lateral direction with respect to its lengthwise direction such as effected when the bushing 4 is shifted within the aperture 6 to align the funnel guide stem over the exact center of the bucket, the turning force applied to spindle 12 reaches a maximum and the device rotates at substantially the speed of rotation of the bucket 2. The degree of rotation may be readily ascertained by observing the bent portion 14. As the center of rotation of the inner bottom surface of the bucket is easily observed when the bucket is rotating rapidly, a further check on the accuracy with which the guide stem is aligned on the axis of rotation of the bucket may be made by looking down into the bucket to determine how precisely the lower end portion of the spindle 12 engages the rotating bucket surface at the center of rotation. When the desired lateral adjustment of the guide 5 is obtained, a nut 16 in threaded relationship with the bushing 4 may be tightened against the lower surface of the bracket to secure a guide at the correctly aligned position.

The spindle 12 may be fashioned from any material having sufficient rigidity that the end portion thereof will not be readily bent when brought into contact with the rotating bottom surface of the bucket. It may be constructed from metallic rod stock, from wood, or from various synthetic resins which are readily shaped into straight rods of the required rigidity. To avoid scoring of the interior bottom surface of the bucket, it is preferred that the spindle 12 be constructed from a material which is relatively light in weight and not as hard as the material comprising the bottom surface of the bucket. For these reasons, the inorganic synthetic resinous materials such as polystyrene, polyamide or nylon resins, hard rubber, and methyl methacrylate resin will be found quite satisfactory for forming a device 12 which produces little or no abrasion on the bucket surface.

In the embodiment of the invention as shown in Fig. 2, a jig 20 which may be T-shaped as shown, is supported by a holder, such as that comprising the bracket 3, the sleeve 4, and the bushing 5. The jig 20 comprises a head portion 21, an elongate shank portion 22 having an internal bore 23 extending also through the head portion, a spirit level indicator 25 secured to the head portion, and an indicator spindle 12 supported within the bore 23 in engagement with the bottom surface of the bucket 2. As shown in Fig. 3, the bore 23 extends centrally through the head portion 21 and axially through the shank portion 22. The spirit level indicator is mounted on the head portion to one side of the bore 23. The lower surface 27 of the head portion is accurately machined or otherwise formed in a plane normal to the axis of the bore 23 and the outer surface of the shank portion 22 so that the jig may be supported by the holder with the surface 27 seated on the upper flanged surface of the bushing 5. The spindle 12a fits within the bore 23 with small clearance so that

the spindle may rotate freely without appreciable frictional restraint and with as little wobble as possible with respect to the axis of the bore. A low viscosity lubricating oil may be introduced within the bore to reduce friction with the spindle.

The spindle 12a is provided with a circumferentially extending indicium at 29 which may take the form of a thin line made by printing or scribing the material of the spindle, or by a small ridge or groove formed in the spindle during the manufacture thereof. Such a mark occurs on the spindle at the point where it will protrude from the bore when the lower end of the spindle engages the bucket and thus indicates a definite spacing of the guide holder with the bottom surface of the bucket. If desired, a plurality of indicia may be provided along the upper part of the shank portion of the spindle to facilitate adjustment of the holder to different settings.

The jig 20 is intended for use in adjusting large pluralities of guide holders to a standard setting. Since it may be used to indicate the levelness with which a funnel guide is supported by its respective holder as well as the variance of the guide portion with a desired setting in the vertical and lateral directions, the jig enables complete and universal adjustment of guide holders. To obtain adjustment of a guide, the jig is inserted from above, into and through the bushing 5, into the position as illustrated in Fig. 2. While supported with the surface 27 in engagement with the top of the bushing 5, the jig is rotated through at least 90 degrees to determine whether the axis of the jig is canted out of vertical alignment. If so, the bracket 3 is shimmed or otherwise adjusted at the place where it is attached (not shown) to bring the bracket in an orientation wherein it will support the jig with its axis in substantially vertical alignment. The condition is obtained when the jig can be rotated through 90 degrees and the bubble of the spirit gage 25 remains centered along the tube thereof.

To obtain a desired lateral adjustment of the assembly comprising the sleeve 4 and the bushing 5 whereby the assembly supports the jig or the guide 1 with its axis coinciding with the axis of rotation of the bucket 2, the nut 16 is loosened and the assembly is moved until maximum rotation of the spindle 12a is obtained. At this juncture, visual inspection may be made, as suggested with respect to spindle 12 of Fig. 1, to ascertain the precision with which the lower end-portion of spindle 12a engages the inner bottom surface of the bucket at its center of rotation. The nut 16 is thereafter tightened to fix the lateral adjustment of the sleeve and the bushing. Vertical adjustment of the bushing 5 to a setting for supporting the funnel guide 1 above the inner bottom surface of the bucket is obtained merely by turning the bushing within the sleeve 4 until the indicium at 29 on the spindle 12a is even with the plane of the top surface 30 of the jig.

In the manner just described, the holder for the guide 1 may be completely and accurately positioned to a desired setting through the use of the jig 20. The present invention provides a simple and inexpensive device for centering funnel guides relative to spinning buckets and is applicable to substantially all of the centrifugal spinning equipment presently used to pro-

duce regenerated cellulose yarn without any need for modification of the equipment.

While preferred embodiments of the invention have been shown and described, it is to be understood that changes and variations may be made without departing from the spirit and scope of the invention as defined in the appended claims.

I claim:

1. In combination with a spinning bucket, means for supporting a funnel guide which has a straight hollow stem portion, said means being transversely adjustable with respect to the axis of rotation of the bucket, an elongate member having a straight passageway and supported by said means with the axis of the passageway extending with respect to said means along the path occupied by the axis of the stem portion of a guide when supported by said means, a device for indicating a substantially centered position of the tip of the stem portion of a funnel guide with respect to the axis of the bucket comprising a spindle having a straight shank portion longer than the passageway and extending through the passageway into engagement with the inner bottom surface of the bucket, and a portion extending laterally from the upper end of the shank portion for facilitating the observation of the rotative speed of the spindle.

2. In combination with a spinning bucket, a funnel guide having a hollow stem portion, and means for supporting the funnel guide, said means being transversely adjustable with respect to the axis of rotation of the bucket, a device for indicating the substantially centered position of the tip of the stem portion with respect to the axis comprising a straight elongate shank portion longer than the stem portion of the guide and extending through the passageway of the stem portion into engagement with the inner bottom surface of the bucket, and a portion extending laterally from the upper end of the shank portion for indicating the rotative speed of the device.

3. In combination with a spinning bucket having a hollow stem portion, and means for supporting the funnel guide, said means being transversely adjustable with respect to the axis of rotation of the bucket, a device for indicating a portion of the tip of the stem portion wherein it is substantially centered with respect to the axis comprising a straight elongate shank portion longer than the stem portion extending through the passageway of the stem into engagement with the inner bottom surface of the bucket, the lower end-surface of the shank portion being complementary to an area centered within the bottom surface of the bucket, and a portion extending laterally from the upper end of the shank portion for indicating the rotative speed of the device.

4. In combination with a spinning bucket, a funnel guide having a hollow stem portion, and means for supporting the funnel guide, said means being transversely adjustable with respect to the axis of rotation of the bucket, a device for indicating a substantially centered position of the section of the stem portion nearest the bottom surface of the bucket with respect to the axis, said device having a rod-like shank portion terminating at one end in a flat surface and at the other end in a section extending laterally from the shank portion, said shank portion being longer than the stem portion of the guide and extending therethrough

at close clearance with the interior surface of the stem portion into engagement with the inner bottom surface of the bucket.

5. A method for centering the end-portion of the stem of a funnel guide with respect to the inner bottom surface of a spinning bucket having an upwardly-extending axis of rotation comprising the steps of inserting a straight rigid elongate loosely-fitting article through the stem of a funnel guide into engagement with the bottom surface of the bucket, rotating the bucket, adjusting the guide laterally with respect to the bucket axis until a portion of the article extending above the guide is observed to rotate at a maximum rate, and securing the guide to a lateral adjustment corresponding to said maximum rate of rotation of the article.

6. In combination with a spinning bucket, means for supporting a funnel guide which has a straight hollow stem portion, said supporting means having a bore for receiving the funnel guide, means for adjusting the supporting means transversely with respect to the axis of rotation of the bucket, a jig having an elongate shank portion and a head portion, said jig having a bore extending axially through the shank portion and through the head portion, the shank portion having an outer surface adjacent the head portion which is substantially coaxial with the bore of the jig and complementary to the bore of the supporting means, an indicator spindle having a shank portion longer than the jig, and a portion extending laterally from one end of the shank portion for facilitating the observation of the rotative speed of the spindle, said shank portion of the spindle extending through the bore of the jig into engagement with the bottom surface of the bucket with said laterally extending portion being supported above the head portion of the jig for unobstructed rotation.

7. In combination with a spinning bucket, means for supporting a funnel guide which has a straight hollow stem portion, said supporting means having a bore and a seating surface concentric with an end of the bore for receiving the funnel guide, means for adjusting the supporting means transversely with respect to the axis of rotation of the bucket, a jig having an elongate shank portion and a head portion, said jig having a bore extending axially through the shank portion and through the head portion, the shank portion having an outer surface adjacent the head portion which is substantially coaxial with the bore of the jig and complementary to the bore of the supporting means, a surface on the head portion extending radially outwardly from said outer surface of the shank portion for engaging the seating surface, a spirit level mounted on the head portion laterally with respect to the bore of the jig and extending transversely with respect to the axis of said bore to indicate the levelness of a plane normal to said axis, an indicator spindle having a shank portion longer than the jig and a portion extending laterally from one end of the shank portion, said shank portion of the spindle extending at close clearance through the bore of the jig in freely slideable and rotatable relationship into engagement with the bottom surface of the bucket, said laterally extending portion being supported above the head portion and the spirit level for unobstructed rotation.
